A. C. RIOUX

OIL SUPPLY INDICATING DEVICE FOR AUTOMOBILE ENGINES

Filed Feb. 16, 1924

FIG. 1.

FIG. 2.

FIG. 3.

INVENTOR
A.C. RIOUX.

BY

J. L. Bley
ATTORNEY

UNITED STATES PATENT OFFICE.

ALFRED CALIXTE RIOUX, OF CLARESHOLM, ALBERTA, CANADA.

OIL-SUPPLY-INDICATING DEVICE FOR AUTOMOBILE ENGINES.

Application filed February 16, 1924. Serial No. 693,355.

To all whom it may concern:

Be it known that I, ALFRED CALIXTE RIOUX, a subject of the King of Great Britain, and a resident of the town of 5 Claresholm, in the Province of Alberta, Canada, have invented certain new and useful Improvements in Oil-Supply-Indicating Devices for Automobile Engines, of which the following is the specification.

10 My invention relates to improvements in oil supply indicating devices for automobile engines, and the object of the invention is to provide means for preventing damage to the engine of an automobile caused by running such engine with insufficient oil supply, and it consists essentially of the arrangement and construction of parts hereinafter more particularly explained.

Fig. 1 is a side elevation of an automobile 20 engine and coil box showing my device applied thereto, part of the engine casing being broken away to exhibit the position and construction of my device.

Fig. 2 is an enlarged perspective detail 25 of my device.

Fig. 3 is a longitudinal sectional view through Fig. 2.

In the drawings like characters of reference indicate corresponding parts in each 30 figure.

1 indicates an automobile engine of any ordinary construction in which are located in the usual position time gears 2 and 3.

4 is the fly wheel of the engine rotating 35 in the oil well 5 in the usual manner so as to throw up oil, which is received at a funnel end 6 of the lubricating pipe 7 which feeds the oil downward to the gearing 2 and 3, such oil returning in the usual manner back to the oil well.

7^x is a magneto,—8 the magneto contact.

9 is the usual opening which is formed 45 in the engine casing and provided with the usual cover plate 10, the opening being located above the brake bands, and through which such brake bands are adjusted.

11 is a coil box provided with a magneto terminal 12. Usually the magneto terminal 12 is connected by a wire to the magneto contact 8. This wire is divided into two portions, as indicated at 13 and 14, the outer end of the portion 13 being connected to the terminal 12, and the outer end of the 50 ——— the magneto contact 8.

The opposite ends of the wires 13 and 14 are connected to the contacts of a switch which I will now describe.

15 is a plate upon which my switch is supported, such plate being interposed between the cover plate 10 and the flange 9^x 60 extending round the orifice 9, the plate 15 being provided with holes 16 through which the usual securing bolts 17 of the cover plate 10 pass, so as to secure the plate 15 in position.

18 and 19 are bearing pieces provided with orifices 20 in which is journaled the reduced ends 21 of a rocking shaft 22.

23 is a drip pan having an inclined bottom 24 inclining downward. The upper 70 end of the drip pan is secured to the rocking shaft 22, as indicated clearly in Fig. 3. Adjacent the lower end of the bottom 24 is located a perforation 25.

26 is an arm secured to the bottom of the 75 drip pan extending rearward therefrom from its point of swing and carrying a counter-balancing weight 27.

28 is a curved rod pivotally secured to a bracket 29 secured to the bottom 24 of the drip pan 23.

The lower portion of the rod 28 is preferably arched so as to be concentric with the centre of swing of the drip pan.

The upper end of the rod 28 extends 85 through an orifice 30 formed in the plate 15 and through an insulated block 31.

32 is a contact finger secured to the rod 28 in proximity to its upper end.

The free end of the wire 14 is connected 90 by nuts 33 and 34 to the upper end of the rod 28 so as to be electrically connected with the finger 32.

35 is a finger secured to the plate 15, and insulated therefrom by an insulating 95 strip 36.

37 is a bolt extending upward from the finger 35 and to which the free end of the wire 13 is secured so as to make a connection to the finger 35.

38 is a deflecting plate secured to the plate 10 and depending therefrom over the drip pan 23 for a purpose which will hereinafter appear.

Having described the principal parts involved in my invention I will now briefly describe the operation of the same.

As the fly wheel 4 revolves it throws up

the oil in the usual manner, which oil is caught by the funnel shaped end 6 of the oil feed tube 7 and conveyed to the gears 2 and 3 according to the common practice.

5 A certain amount of this oil which is caught up in this way is also caught by the plate 38 and drips downward into the drip pan 23. The perforation 25 is of such a size as to cause the pan to retain some of 10 the oil dripped thereinto. The weight of such oil in the pan 23 is sufficient to counter-balance the weight of the counter-weight 27, causing the pan 23 to tilt downward and carrying the contact finger 32 into engagement 15 with the finger 35, thereby closing the ignition circuit.

During the running of the gear, and when the engine is supplied with a normal amount of oil, the amount thrown up by the fly 20 wheel is sufficient to hold the contact fingers 32 and 35 in engagement.

When, however, the supply of oil begins 25 to run low, sufficient is not thrown up to maintain this quantity in the drip pan 23 when such quantity is constantly being reduced by the oil dripping through the perforation 25.

When the amount of oil passing through 30 the perforation 25 is greater than the amount of oil which is thrown into the drip pan 23, the weight of the drip pan is lessened, and consequently the counter-weight 27 raises 35 the drip pan, carrying the finger 32 out of engagement with the finger 35 and thereby breaking the ignition circuit, immediately informing the driver that he is running out of oil.

When using my device, it is advisable that 40 the driver take with him an emergency supply of oil, so that should his supply run

out, and the ignition circuit be broken so as to prevent the running of the car, he can immediately supply the oil well with sufficient oil to enable him to proceed.

Although I have shown my device as connected with the ignition circuit operating to open and close, other indicating devices might be employed such as a small lamp, the circuit of which is opened and closed by contacts such as 32 and 35, so that immediately the supply of oil runs low, the lamp will be lit and thereby indicate to the driver such condition.

What I claim as my invention is:

In an automobile engine, the combination 55 with the transmission casing having the usual openings set in an incline and a cover for such opening, of a pan adapted to receive the oil thrown up by the fly-wheel and having an orifice in the bottom thereof 60 through which such received oil is adapted to leak, and a counter-weight lever secured to the pan forming with the pan generally an obtuse angle, a pivot mounting for the pan carried by the cover adjacent the apex 65 of the aforesaid angle, an arc shaped rod pivotally mounted at its lower end to the pan bottom within the pan and extending outward freely through the cover and insulated therefrom, a contact finger carried by the outer end of the rod, and a stationary contact carried by the cover and insulated therefrom, such contact finger forming the terminals of an ignition circuit, such contacts being held in engagement by the weight 70 of the oil within the pan and adapted to break contacts as the oil leaks out of the pan through the aforesaid orifice.

ALFRED CALIXTE RIOUX.
